(57) **CLAIM**

The ornamental design for an electrical connector as shown and described.

DESCRIPTION

FIG. 1 is a top, right, front perspective view of an electrical connector according to our design;

FIG. 2 is a top, left, front perspective view thereof;

FIG. 3 is a bottom, left, rear perspective view thereof;

FIG. 4 is a bottom, right, rear perspective view thereof;

FIG. 5 is a front elevation view thereof;

FIG. 6 is a rear elevation view thereof;

FIG. 7 is a top plan view thereof;

FIG. 8 is a bottom plan view thereof;

FIG. 9 is a right side elevation thereof; and,

FIG. 10 is left side elevation view thereof.

The Dash-Dash broken line portion of the figure drawings is included to show portions of the article that form no part of the claimed design. The Dash-Dot broken line portion of the figure drawings is included to show claim boundaries that form no part of the claimed design.

1 Claim, 7 Drawing Sheets
